UNITED STATES PATENT OFFICE

EDWARD L. FAIRBANKS, OF GLENDALE, CALIFORNIA, ASSIGNOR TO CONTINUOUS RAIL CROSSING CORPORATION, OF RENO, NEVADA, A CORPORATION OF NEVADA

ELECTRIC RAIL CROSSING

Application filed February 29, 1928. Serial No. 257,939.

My invention relates to rail crossings of the general type disclosed in my copending application entitled "Rail crossing," Serial Number 247,305, which has matured into 5 Patent No. 1,729,098, September 24, 1929, and in which a pair of intersecting tracks are provided with revolvable turntables at their intersections, the turntables having grooves which are adapted to be alined with either 10 of the tracks in order to provide a continuous, smooth passage for a vehicle travelling thereover.

An object of my invention is to provide an automatic means for actuating the turntables.

15 Another object of my invention is to provide an electric actuating system for the turntables.

A further object of my invention is to insure that the turntables are at all times urged 20 toward either of their extreme positions.

My invention possesses other advantageous features, some of which with the foregoing will be set forth at length in the following description where I shall outline in full that 25 form of the electric rail crossing of my invention, which I have selected for illustration in the drawings accompanying and forming part of the present specification. In said drawings I have shown one form of rail crossing 30 embodying my invention, but it is to be understood that I do not limit myself to such form since the invention, as set forth in the claims, may be embodied in a plurality of forms.

35 In the drawings:

Fig. 1 is a plan of the intersection of two pairs of tracks showing the electric actuating mechanism of my invention installed.

Fig. 2 is a cross section on the line 2—2 of 40 Fig. 1.

Fig. 3 shows in diagrammatic form the wiring for the electric circuits at one of the intersections embodying my rail crossing.

Fig. 4 is a cross section on the line 4—4 of 45 Fig. 1.

Fig. 5 is a transverse section on the line 5—5 of Fig. 4.

The electric rail crossing of my invention 50 preferably comprises a pair of intersecting rails having a rotatable turntable at their in-

tersection, the turntable being provided with a groove adapted to aline with either of said rails, together with electric means for urging the turntable into either of its extreme positions.

In a typical installation of my electrical rail crossing, there are preferably provided a pair of intersecting rails 106 and 107 either joined to or formed integrally at their intersection with a casing 108. Within the 60 casing is situated a turntable 109 preferably having a diametral groove 111 extending thereacross adapted to aline with either of the rails 106 or 107.

In order to rotate the turntable 109, there 65 is preferably provided integrally therewith a depending extension 112 having a squared portion 113 at its lower end to engage a suitably apertured lever 114 secured in place by a fastener 116. Oscillation of the lever 114 70 rotates the turntable 109. In order to insure that the groove 111 is in exact alinement with the rails 106 and 107 when the turntable is in either of its two extreme positions, a stop is preferably provided on the 75 extension 112 comprising a projection 117 operating in a cylindrical slot 118 provided in the casing 108.

Means are provided for actuating the turntables electrically. Preferably, linkage 80 119 joins a plurality of cranks 114 for the various turntables 109, and this linkage can be provided with suitable adjustments 121 in order to dispose it properly for the correct actuation of the turntables. Instead of the 85 usual mechanical means for moving the turntables, I preferably provide an electric means. This is ordinarily embodied as a solenoid 122 suitably affixed in a housing 123, the solenoid being arranged to move the 90 linkage 119 in either axial direction to rotate the turntables from one extreme position to the other. Further, the solenoid is sufficiently powerful to transmit force thru the linkage tending to cause the turntables to rotate 95 farther than their extreme positions. They are restrained, however, by the projections 117 operating in the slots 118. In this manner, the grooves 111 cannot be in misalignment with the rails, as the urging of the sole- 100

noid always causes the faces of the projections 117 to seat firmly against the faces of the slots 118.

In order to prevent movement of the linkage accidentally, there is provided an interlock which usually includes a solenoid 124 controlling the movement of a plunger 126 adapted to pass thru suitable perforations 127 in the linkage. When the plunger is shot 5 home thru the perforations, the linkage 119 is incapable of movement and the plunger must be withdrawn prior to operation of the turntables.

As shown in Fig. 3, I preferably provide 15 means for automatically actuating the various solenoids 122 and 124 in proper sequence so that the turntables will automatically be positioned in accordance with the requirements of traffic passing along the tracks 106 20 and 107. Energization of the solenoids is preferably effected thru circuits which are completed by vehicles passing over the track, in the well known manner. One circuit includes a contact 131, preferably on the trolley wire, which energizes certain coils 132 of 25 the solenoids 124 in order to withdraw the plungers 126 from the apertures 127. This circuit is completed when a vehicle passes along the track 107, for instance, and unlocks the linkage 119. Additional movement of the vehicle along the track causes the trolley to close a circuit through a contact 133 thereby energizing certain coils 134 of the 30 main solenoids 122. The energized solenoids 35 actuate the linkage 119 to revolve the turntables 109 in such a manner that the grooves 111 align with the tracks 107. Further progress of the vehicle causes a circuit to be completed thru a contact 136 which energizes 40 coils 137 of solenoids 124, causing the plungers 126 to be shot home thru the perforations 127 in the linkage. The turntables 109 are first properly positioned and then locked 45 against further rotation during the passage of a vehicle across the intersection.

A similar operation occurs when a vehicle approaches on track 106. A circuit is closed thru a contact 141 which withdraws the plungers 126 from the apertures 127. Then 50 a contact 142 closes a circuit which energizes coils 143 in the solenoids 122 tending to move the linkage properly to revolve the turntables 109 with the grooves 111 in correct alignment with the rails 106. Further progress of the 55 vehicle causes a circuit to be closed by means of a contact 144 which again positions the plungers within the perforations preventing further movement of the linkage.

It will be appreciated that suitable 60 circuits can be provided so that the solenoids will be actuated by vehicles approaching from either direction on either of the tracks and that various circuits can be provided for actuating all of the intersections arranged in 65 the manner shown in Fig. 1. With the elec-

trical rail crossing of my invention, there is no manual supervision required and furthermore, there is assurance that despite possible maladjustment of the linkage, the solenoids always tend to cause the turntables to move 70 into their extreme positions to provide perfect alinement between the grooves and the rails.

I claim:

1. An electric rail crossing comprising a 75 casing at the intersection of two rails, a turntable in said casing, said turntable having a groove adapted to align with either of said rails, linkage for rotating said turntable, means for locking said linkage, a solenoid 80 for locking and unlocking said locking means, and a solenoid for actuating said linkage.

2. An electric rail crossing comprising a casing at the intersection of two rails, a turntable in said casing, said turntable having a 85 groove adapted to align with either of said rails, a link for rotating said turntable, a plunger adapted to restrain said link against movement by engaging an aperture therein, a solenoid for withdrawing said plunger from 90 said aperture, and for returning said plunger to engage another aperture in said link, and a solenoid for actuating said link.

3. An electric rail crossing comprising a 95 casing at the intersection of two rails, a turntable in said casing, said turntable having a groove adapted to align with either of said rails, a link for rotating said turntable between two extreme positions, a solenoid for actuating said link tending to rotate said 100 turntable beyond said extreme position, means on said turntable engaging said casing to limit the movement of said turntable at either of said extreme positions, a plunger adapted to restrain said link against movement by engaging an aperture therein when 105 said turntable is at one of said extreme positions, and a solenoid for withdrawing said plunger from said aperture and for returning said plunger thereto.

In testimony whereof, I have hereunto set my hand.

EDWARD L. FAIRBANKS.
